US0D1093345S

(12) **United States Design Patent** (10) **Patent No.:** **US D1,093,345 S**
Zhan (45) **Date of Patent:** **** Sep. 16, 2025**

(54) **DISPLAY SCREEN WITH GRAPHICAL USER INTERFACE CONTROLLER**

(71) Applicant: **Haitao Zhan**, Shenzhen (CN)

(72) Inventor: **Haitao Zhan**, Shenzhen (CN)

(**) Term: **15 Years**

(21) Appl. No.: **29/855,988**

(22) Filed: **Oct. 10, 2022**

Related U.S. Application Data

(63) Continuation-in-part of application No. 29/821,458, filed on Dec. 30, 2021, now Pat. No. Des. 1,070,815.

(57) **CLAIM**

The ornamental design for a display screen with graphical user interface controller as shown and described.

DESCRIPTION

FIG. 1 is a front elevational view of a first embodiment of a display screen with graphical user interface controller showing my new design; and, FIG. 2 is a front elevational view of a second embodiment of the display screen with graphical user interface controller. The broken lines showing a display screen illustrate portions of the article that form no part of the claimed design.
